UNITED STATES PATENT OFFICE.

BENJAMIN HIRSCHHORN, OF NEW YORK, N. Y., ASSIGNOR TO MILLIE PATENT HOLDING CO. INC., OF NEW YORK, N. Y., A CORPORATION OF NEW YORK.

TEA CARTRIDGE.

Application filed September 26, 1923. Serial No. 664,880.

To all whom it may concern:

Be it known that I, BENJAMIN HIRSCHHORN, a citizen of the United States, and resident of the city of New York, in the 5 county of Bronx and State of New York, have invented certain new and useful Improvements in Tea Cartridges, of which the following is a specification.

The present invention relates to cartridges 10 for percolating or extracting the flavor from tea-leaves or coffee. The invention pertains more particularly to that type of tea-cartridges, which is described in U. S. Letters Patent No. 1,310,796, granted to me on July 15 22, 1919.

In the Letters Patent mentioned, a device 20 for extracting essence from tea-leaves or coffee is described, comprising a bag of textile fabric which contains a quantity of tea-leaves or coffee just sufficient for a single brewing. The mouth of the bag is drawn into folds and closed by a metal strip, engaging and compressing said folds, thereby closing the mouth of said bag, said strip attaching at the same time a suspending string 25 to said bag.

The main object of the present invention is to provide a cartridge the bag of which is in the form of a tube, both ends of the 30 tube being closed by a metal strip of the type above referred to.

With these and other objects in view, which will more fully appear as the nature of the invention is better understood, the 35 same consists in the combination, arrangement and construction of parts hereinafter described, pointed out in the appended claims and illustrated in the accompanying drawings, it being understood that many 40 changes may be made in the size and proportion of the several parts and details of construction within the scope of the appended claims, without departing from the spirit or sacrificing any of the advantages 45 of the invention.

One of the many possible embodiments of the invention is illustrated in the accompany drawings, in which:

Figure 1 is an elevation of a tea cartridge 50 constructed in accordance with the present invention; Fig. 2 is an elevation, on a larger scale, of the tube of which the bag is formed, having already attached to it a suspending string, the tube being turned inside out in 55 order to more clearly show the elements;

and Fig. 3 is a section taken on line 3—3 of Fig. 2, on a still larger scale, the tube being turned so as to conceal the seam running along one of its longitudinal edges.

In the drawings, the numeral 10 indicates 60 a tube of open mesh textile fabric, such as for instance cotton, it being made of a single piece of fabric that is folded along one of its longitudinal edges, denoted by the numeral 11, the meeting longitudinal edges 65 11' of the two plies being joined by a row of stitches 12, which runs parallel to the said meeting edges. The stitches serve at the same time to fasten to the tube a suspending string 13, extending from the lower transverse edge 14 of the tube along the meeting edges 11' in parallel relation to the latter and thence beyond the upper transverse edge 15 of the tube a substantial distance beyond 70 said upper transverse edge, a handle 16 of 75 pasteboard or like material being attached in any suitable manner to the free end of the string, for a purpose hereinafter to be described. In preparing the tea cartridge, the tube is first turned so that the meeting edges 80 11' of the material are disposed between the plies thereof, as clearly shown in Fig. 3 of the drawings. Thereafter the lower end of the tube is gathered into folds and a metal strip 17 applied thereto. This metal strip 85 is shaped to assume the form of a ring, embracing the folded portion of the tube so as to hold the folds under compression. In this manner a bag is formed, tea-leaves or coffee for a single brewing being then placed 90 into the same. The mouth of the bag is then closed by puckering the same and applying thereto a metal strip 18, also shaped to assume the form of a ring so as to prevent escaping of the contents. Both metal rings, 95 besides that they close the top and bottom of the tube, serve also to securely hold the suspending string in place upon the cartridge.

In brewing tea or coffee with the improved device, the cartridge is taken hold of by its handle 16 and lowered into the brewing receptacle, the free end of the string and handle being permitted to hang over the mouth of the receptacle, after which 100 its cover is put in place. The cover thus holds the free end of the string and handle ready for further operation. Into the receptacle is poured, either before or after the insertion of the cartridge, a suitable quantity 105 110

of boiling water. When sufficient essence has been extracted from the tea-leaves or coffee within the cartridge, the cover of the brewing receptacle is removed and the bag withdrawn by grasping its handle.

What I claim is:—

1. A device for extracting essence from tea-leaves or coffee, comprising a tube of textile fabric having both ends drawn into 10 folds, a metal strip encircling and compressing the folds on each end of the tube for closing said ends, and a suspending string held in place by both metal strips.

2. In a device according to claim 1, said 15 string being also attached to said tube by a row of stitches.

3. In a device according to claim 1, said string being also attached to said tube by a row of stitches passing through the plies of the material in forming said tube,

20

4. A device for extracting essence from tea-leaves or coffee, comprising a tube of textile fabric having both ends drawn into folds, a metal strip encircling and compressing the folds on each end of said tube for 25 closing said ends, and a suspending string attached to said tube.

Signed at New York, in the county of New York and State of New York, this 25th day of September, A. D. 1923.

BENJAMIN HIRSCHHORN.
